UNITED STATES PATENT OFFICE.

ALFRED WIEHL, OF NEW YORK, N. Y.

ADVERTISING-FAN.

SPECIFICATION forming part of Letters Patent No. 290,827, dated December 25, 1883.

Application filed July 12, 1883. (No model.)

To all whom it may concern:

Be it known that I, ALFRED WIEHL, of the city, county, and State of New York, have invented certain new and useful Improvements 5 in Advertising-Fans, of which the following is a specification.

This invention has reference to an improved advertising-fan of novel and attractive design; and it consists of a fan the body of which 10 is covered with a layer provided with openings, behind which a sliding piece, that complements a suitable picture on the covering-layer, is arranged. The sliding piece is attached at one side by an elastic to the fan-body, and at the other side is provided with 15 a string or other means, by which motion can be given to the sliding piece, and thus a transformation of the picture be produced.

In the accompanying drawings, Figures 1 20 and 2 represent front views of my improved advertising-fan, showing the slide-piece in different positions. Fig. 3 is a vertical transverse section through the center on line x x , Fig. 1.

25 Similar letters of reference indicate the corresponding parts.

Referring to the drawings, A represents a fan, preferably a common Japanese fan, having a hollow handle, A'.

30 A² is a covering layer, of paper, that is applied to one or both sides of the fan, and provided with a suitable picture, and furnished with openings a a .

Back of the openings a a a slide-piece, B, is 35 guided, which slide-piece is so painted or printed as to complement the picture on the

covering layer or layers A² of the fan. The upper part of said slide-piece B is attached to the body of the fan by means of a piece of rubber, b, or other elastic material, while to its 40 lower part a string, B', is attached, which passes, preferably, through the hollow handle A', and has a ring, B'', attached to its outer end. By pulling at the string B' the slide-piece B is moved, so as to produce a transformation of the picture, whereby a comical or otherwise striking effect is produced. 45

In place of the string any other equivalent means for reciprocating the slide-piece may be used. 50

The fan may be made in any desired design, and produces, in connection with its reciprocating slide-piece, an attractive and amusing effect, whereby the fan is specially adapted to advertising purposes. 55

Having thus described my invention, I claim as new and desire to secure by Letters Patent—

A fan, A, having a hollow handle, A', a suitable picture on a layer, A², of paper furnished with openings a a , the slide-piece B back of 60 the openings, painted or printed to complement and complete the picture, the elastic b, attached to the slide-piece and the body of the fan, and the string B', extending through the handle, substantially as described. 65

In testimony that I claim the foregoing as my invention I have signed my name in presence of two subscribing witnesses.

ALFRED WIEHL.
